UNITED STATES PATENT OFFICE.

FREDERICK E. LARGE, OF SYRACUSE, NEW YORK.

AUTOMOBILE LOCK.

Application filed June 8, 1922. Serial No. 566,841.

To all whom it may concern:

Be it known that I, FREDERICK E. LARGE, a citizen of the United States, residing at Syracuse, in the county of Onondaga and State of New York, have invented certain new and useful Improvements in Automobile Locks, of which the following is a specification.

This invention relates to improvements in automobile locks, and has for its object to provide novel, simple and effective means for preventing theft or the unauthorized use of motor vehicles. A further object is to provide an independent throttle valve, which is disposed in the main gas passage between the carburetor and the intake manifold of an internal combustion engine, by means of which the explosive gas necessary for starting and operating the engine may be entirely shut off, while the vehicle is left standing on the street or in a garage. A further object is to provide a novel mechanism which is supported by the independent valve, with which is associated a dial having numbered graduations, and a pointer, which may be swung around the dial and into registry with certain of the numbers, for selectively moving and setting certain parts of said mechanism, for effecting the unlocking and opening of said valve, and for allowing the explosive gas to pass from the carburetor to the cylinders for operating the engine. A further object is to provide novel means for secretly selecting and arranging the combination of numbers on the dial, and for correspondingly positioning the parts of said mechanism so that the valve may be opened or closed at will by the person to whom the combination is known. And a further object is to provide novel means for preventing unauthorized persons from ascertaining and working the secret combination.

I attain these objects by the means set forth in the detailed description which follows, and as illustrated by the accompanying drawing, in which—

Figure 1 is a side view of an internal combustion engine, to which my improvement is applied. Fig. 2 is an enlarged top plan view of the locking valve and related parts, the valve being in the closed position. Fig.

3 is a similar view showing the locking valve open. Fig. 4 is a front side elevation of the same. Fig. 5 is an enlarged central vertical longitudinal section taken on line 5—5 of Fig. 2. Fig. 6 is a central vertical cross-section taken on line 6—6 of Fig. 2. Fig. 7 is respectively an end and a side view of the split ring which encloses the tumblers. Fig. 8 is respectively a top plan and an edge view of the (butterfly) locking valve. Fig. 9 is respectively an edge and a face view of one of the end tumblers. Fig. 10 is respectively an edge and opposite face views of the central tumbler. Fig. 11 is respectively a face and an edge view of the opposite end tumbler. Fig. 12 is an enlarged face view of the combination dial, which is located on the dash. Fig. 13 is an enlarged view of the tumbler and valve shaft. Fig. 14 is a face view of the blank dial. Fig. 15 is respectively a top face, a side, a rear face, and a rear end view of the locking member. And Fig. 16 is a detail view showing the latter member in the position for unlocking the valve.

In the drawings, 2 represents the cylinders of an internal combustion engine, and 2' the intake manifold, the latter having a down leg 2^a, which terminates in a horizontal flange 2^b. 2^c represents the carburetor having an upwardly facing flange 2^d, which parallels, and is spaced from the flange 2^b, and 2^e is a fragment of the dash of the vehicle, which supports certain of the operating parts of the locking mechanism.

My improved locking mechanism consists of the following parts: 3 is a body which preferably conforms in size and shape to the flanges 2^b—2^d, and the said body is preferably disposed between and registers with the said flanges, as best seen in Fig. 1. The body 3 has a relatively large central opening 3', which registers with the usual corresponding circular gas passages, of the carburetor, and the down leg 2^a of the manifold. The body 3 is also provided near its ends with perforations 3^a, which receive bolts 3^b that secure the body 3 and the flanges 2^b—2^d in place, as shown in Fig. 1. The body 3 is bored out transversely, as at 3^c, to receive a shaft 4, which extends diametrically across the central opening 3', one end 4' of the

said shaft being journalled in a socket 3^d of the body 3, while the opposite end 4^a projects some distance beyond the front edge of the said body. 5 represents a "butterfly" 5 throttle valve, which consists of a flat disk which is pivotally disposed in and controls the opening 3' of the body 3, the said valve being loosely mounted on the shaft 4, which passes through a bored-out cylindrical portion 5', that extends diametrically across the disk 5. The disk 5 rotates with the shaft 4 at certain times, for controlling the outflow of the gas from the carbureter to the engine 2, to the extent shown by comparing Figs. 10 2, 3 and 4.

The opening of the valve 5 is controlled directly by a number of tumblers 6, 7 and 8, which are mounted on the shaft 2 and concentrically with the barrel 5' of the disk 20 5, the said barrel being cut away, as at 5^a, to receive the tumblers and also a split holding ring 9, which closely encircles and conceals the three tumblers, as shown in Figs. 2, 3, 5 and 6. The middle or driving 25 tumbler 7 is preferably rigidly attached to and is rotated by the shaft 4, by means of a set screw 7', which engages a flat portion 4^b of said shaft. The outer tumblers 6 and 8 like the disk 5 are loosely mounted on the shaft 4, and the tumblers are rotatable in opposite directions by the tumbler 7, by means of radial teeth 7^a and 7^b, the latter being pitched in opposite directions (see Fig. 10), and engage corresponding radial 30 shoulders 6' and 8' of the other tumblers. The shoulders 6'-8' which face in opposite directions, are formed by the free ends of circular springs, that are rigidly mounted on the facing sides of the tumblers 6 and 40 8. These shoulders are preferably arranged to flex towards the tumblers 6 and 8, for allowing the teeth 7^a and 7^b to pass idly over said shoulders when the tumbler 7 is rotated in the non-driving directions. By this 45 construction and arrangement, the turning of the shaft 4 in the clock-wise direction rotates the tumbler 6, without disturbing the tumbler 8, and when tumbler 7 is rotated in the opposite direction it rotates the tumbler 50 8, without moving the tumbler 6. The split ring 9 exerts enough tension to frictionally hold the tumblers 6 and 8 against accidental rotation, when the tumbler 7 is being rotated in the non-driving directions. The 55 tumblers are all provided with similar peripheral notches, as 6^c, 7^c, 8^c, which are adapted to be brought into alignment, by the forward and backward turning of the shaft 4 and the tumbler 7, for effecting the 60 opening and closing of the disk-valve 5, thereby preventing or permitting the operation of the engine. The locking of the disk 5, is effected by a reciprocatable locking member 10, which is slidable in a self-re- taining guide-groove 10' which is formed in the top face of the disk 5. For this purpose the opposite margins 10^a of the said groove are under-cut, to receive the correspondingly beveled lateral edges of the member 10, as best seen in Figs. 8 and 13. The 70 groove 10' is disposed at right angles to the shaft 4 and the axis of the tumblers carried by said shaft, and said locking member is normally controlled by a spring 11 (see Fig. 2), which exerts its tension for holding all 75 of the tumblers stationary, when the notches 6^c, 7^c and 8^c are brought into alignment, as shown in Fig. 16, and when the locking member enters the said aligning notches, the disk 5 may be rotated, by turning the shaft 80 4 in the right direction, for opening the port or passage 3' in the body 3 for allowing the explosive gas to flow from the carbureter towards the engine cylinders 2. The disk valve 5 is held in the locked and closed 85 position, shown in Figs. 2, 4, 5 and 6, by a latch 12, which is carried by the locking member 10. This latch is loosely disposed in a recess 10^a, which is formed in the bottom face of the said member, and said latch 90 is provided with a reduced portion 12', which projects beyond the outer end of the member 10 and also beyond the adjacent peripheral margin of the disk 5, where said reduced portion is received in a socket 3^e 95 of the body 3, which prevents the tilting or rocking of the disk 5, as from the closed position shown in Figs. 2, 4, 5 and 6, to the open position shown in Fig. 3. The latch 12 is normally under the control of a spring 100 12^a, which exerts its tension for holding the point 12' in the socket 3^e, as long as the member 10 is held away from the notches 6^c, 7^c and 8^c, as shown in Fig. 5. When however, the said notches are brought into 105 alignment (see Fig. 16), by the opposite rotary movements of the shaft 4 and the tumbler 7, the spring 11 moves the locking member 10 towards the tumblers, and this releases the latch 12' from the socket 3^e, for 110 allowing the disk 5 to be swung to the open position, shown in Figs. 3 and 4. As long as one or more of the tumblers 6, 7 or 8 are so positioned that their peripheral notches are out of registry with the inner end of 115 the locking member 10, the said latch will be in engagement with the socket 3^e (see Fig. 5). The inner end of the locking member 10 is slightly beveled or round, so that when the shaft 4 is rotated while the said member is seated in the aligning notches of the tumblers (see Fig. 16), the said locking member 10 may be forced outwardly 120 and into the locking position, shown in Figs. 2 and 5. By this construction and arrangement after the owner has operated the vehicle for a time, and desires to stow it away in a garage, or park it on the street, 125

he may effect the locking of the vehicle against theft or unauthorized use, simply by rotating the shaft 4 sufficiently to throw one or more of the tumblers 6, 7 or 8 into the released position, as shown in Fig. 5, which will permit the closing of the valve 5. After this is done, the valve 5 cannot be again opened except by rotating the shaft 4 forwardly and backwardly in accordance with a secret combination of numbers or positions, for bringing the peripheral notches of the tumblers again in alignment for releasing the latch 12, as described.

The shaft 4 and the tumblers 6, 7 and 8 are operated by the following mechanism: 13 represents a bevel gear, which is rigidly mounted on the outer or free end of the shaft 4. This gear meshes with and is driven by a similar gear 13', which is mounted on one end of a rod 14. The opposite end of the rod 14 extends rearwardly and passes through the dash 2^e, and through a dial 15, which is carried by the dash (see Figs. 1 and 12). The dial 15 is provided with regularly spaced radial graduations 15', and certain evenly spaced graduations are given index numerals, which in the present case show a run from 1-12. A pointer 15^a is mounted on the outer end of the shaft 14 and sweeps the dial in a well-known manner. Beyond the pointer the rod 14 is fitted with a hand-knob 15^b, by which the driver of the vehicle may manipulate the pointer and shafts 14 and 4, for rotating the tumblers 6, 7 and 8 in the proper directions for either unlocking or locking the valve 5, as described. 16 represents what will be referred to as the blank dial, which is mounted on shaft 4 between the gear 13 and the body 3 (see Figs. 1, 2 and 4), and 16' represents a pointer carried by the shaft 4, and is arranged to sweep the dial 16. The pointer 16' is supported by a sleeve 16^a, which is adjustably held in place by a set-screw 16^b.

When my locking mechanism is installed on a vehicle, the owner selects and arranges his own combination, by which the locking and unlocking of the valve 5 may be effected. To accomplish this, he manipulates the shaft 4 in different directions, for ascertaining the proper movements and positions of the three tumblers, for unlocking and opening the valve 5. To do this he first turns the shaft 4 clockwise until the tooth 7^a of tumbler 7 engages shoulder 6' of tumbler 6, and he continues rotating said shaft until the peripheral notch 6^c registers with the locking member 10. He then makes a mark, as at 9 (see Fig. 14) with a lead pencil or other readily effaceable substance, on the blank dial 16 for indicating the first position of the combination. He next rotates shaft 4 in the opposite direction, without disturbing the tumbler 6, until the tooth 7^b engages the shoulder 8' of the tumbler 8, and continues

the said rotation until the notch 8^c of the tumbler 8 is brought opposite the locking member 10, after which he marks the blank dial 16, as at 3, to indicate the second position of the combination. He then turns the shaft 4 in the clock-wise direction again until the notch 7^c of the driving tumbler 7 is brought into alignment with the notches of the other tumblers, and he finally marks the blank dial, as at 12. 75 This last marking indicates that the valve 5 may then be opened (see Figs. 3 and 16). At the end of this last operation of the shaft 4, the locking member 10 is forced into the aligning notches by the spring 11, 80 which withdraws the latch 12' from the socket 3^e. After these preliminary steps for arranging the secret combination have been taken, as described, the owner of the vehicle takes hold of the knob 15^b at the dial 15, and 85 turns the several shafts until the pointer 16' registers with the first temporary marking (9) of the blank dial 16. He then looks at the dial 15 and notes the position of the pointer 15^a (which may or may not correspond with the marking 9 of the blank dial, owing to the adjustment of the pointer 16'), which for example, points to the graduation numbered 9. He next turns the knob 15^b in the reverse direction, until the pointer 16' 90 points to the second marking (3) on the blank dial, and he again notes that the hand 15^a points to the graduation 3 on the dial 15. He then turns the knob 15^b in the opposite direction until the pointer 16' comes to the 100 third marking (12) on the blank dial, and he finally notes that the hand 15^a points to the graduation numbered 12 on dial 15. He charges his memory or writes down the secret combination, which for example, corresponds to the numeral 9-3-12 on the dial 105 15. The foregoing describes how the secret combination, after it is once established, may be worked by the manipulation of the pointer 15^a on the dial 15. When the pointer 110 15^a has been swung around to the last position, as 12, the notches 6^c, 7^c and 8^c of the three tumblers are brought into alignment and the locking member 10 is moved into said notches by the spring 11 for releasing 115 the latch 12 from the socket 3^e. This releases the valve 5, but it is still closed. In order to open the valve 5 it is necessary for the operator to continue the last described movement of the pointer 15^a in the same direction, past the number 12 on the dial 15, until it comes to a stop. This additional movement of the pointer 15^a, swings the valve 5 and related parts, from the closed position shown in Fig. 2, to the open position shown in Fig. 3, and the engine may then be started. When he has completed the selection of his secret combination at the dial 15, as explained, the owner of the vehicle should erase the temporary markings 120 130 135

on the dial 16, after which he should loosen the set screw 16^b, and swing and reset the pointer 16' in some other position, than the one the said pointer occupied, while he was 5 selecting and noting his combination. By this means, strangers to the secret combination, will be unable to hit upon the exact 10 operation of the device, for effecting the opening of the valve 5. If the owner of a car equipped with my locking device wishes 15 to change the combination, he may do so by repeating the foregoing preliminary steps. For example, to select a new combination, the pointer 16' should first be loosened and 20 reset, as described, and then the several tumblers should be rotated in the order named, until their peripheral notches align 25 and register with the locking number 10. New temporary marking should be made on the dial 16, and afterwards the new numbers on the dial 15 should be noted as 30 described. In this way a great many different combinations may be selected, and the evidence of each selection may be entirely 35 destroyed, by simply erasing the markings on the dial 16, and then resetting the pointer 16'.

What I claim, is—

1. The combination with an internal combustion engine including a carbureter connected with the engine cylinders by a common gas passage, of a rockable valve pivoted in said passage, a member carried by 30 said valve for locking the valve in the closed position, a mechanism carried by said valve 35 for normally holding said member in the locking position, a shaft supporting said valve and said mechanism, means for operating said mechanism for releasing said member, and means for operatively connecting 40 said shaft with said valve for opening and closing the valve.

2. The combination with the carbureter and the intake manifold of an internal combustion engine, of a butterfly valve interposed 45 between said carbureter and said manifold and controlling the flow of explosive gas between said parts, a reciprocatable member carried by said valve adapted to lock the valve in the closed position, 50 a shaft for pivotally supporting said valve, means operable by said shaft for reciprocating said locking member, and means operable by said shaft and cooperating with said locking member for opening and closing 55 said valve.

3. The combination with a carbureter and an intake manifold, said parts being connected by a common gas passage, of a disk valve disposed in said passage and controlling 60 the flow of gas from the carbureter to said manifold, a reciprocatable member for locking said valve in the closed position, a shaft for pivotally supporting said valve, means for holding said member in the locking 65 position for preventing the opening of

said valve, a spring for moving said member away from the locking position, and means for operatively connecting said member with said shaft for effecting the opening and closing of said valve. 70

4. The combination with a carbureter and an intake manifold, said parts being connected by a common gas passage, of a valve disposed in said gas passage and controlling the flow of gas therethrough, a reciprocatable member for locking said valve in the closed position, a shaft for pivotally supporting said valve, tumblers carried by 75 said shaft and adapted to move said member towards the locking position, tension means for moving said member away from the locking position, and means for interlocking said member with said tumblers for effecting the opening of said valve. 80

5. The combination with the carbureter 85 and the intake manifold of an internal combustion engine, of a disk valve interposed between the carbureter and said manifold and controlling the flow of explosive gas between said parts, a reciprocatable member carried by said valve adapted to lock the valve in the closed position, a spring exerting its tension for moving said member away from the locking position, a shaft for pivotally supporting said valve, means 90 operable by said shaft for holding said member in the locking position against the tension of said spring, and means for operatively connecting said member with said shaft for effecting the opening of the 95 valve. 100

6. The combination with the carbureter and the intake manifold of an internal combustion engine, of a butterfly valve pivotally disposed in the gas passage extending between the carbureter and the manifold, a member carried by said valve adapted to lock the valve in the closed position, a shaft for supporting said valve, a plurality of tumblers carried by said shaft and having peripheral notches, one of said tumblers being movable with said shaft and adapted when rotated in opposite directions to rotate the other tumbler for bringing said notches into alignment, means for moving said member into engagement with the notches for effecting the releasing of said valve, and means for opening and closing said valve while said member is engaging said notches. 115 120

7. The combination with the carbureter and the intake manifold of an internal combustion engine, of a valve disposed in the gas passage that connects said parts, a shaft supporting and operating said valve, tumblers mounted on said shaft and supported by said valve, one of said tumblers being rigid to said shaft, and a locking member carried by said valve and movable towards and away from said tumblers adapted to 125 130

engage said tumblers for releasing said valve and for allowing said shaft to rotate said valve.

8. The combination with a carbureter and an intake manifold, of a locking device interposed between said parts, a valve carried by said device and rotatable for opening and closing the gas passage extending between the carbureter and said manifold, a shaft for supporting said valve, a plurality of tumblers carried by said valve and operable by said shaft, a locking member carried by said valve and movable towards and away from said tumblers, a latch carried by said member adapted to hold said valve in the closed position when said member is held extended by said tumblers, means for rotating said tumblers for effecting the interlocking of said member with the tumblers for releasing said latch, and means for swinging said valve around the axis of said shaft while said latch is released.

9. The combination with the carbureter and the intake manifold of an internal combustion engine, of a valve disposed in the gas passage leading from the carbureter to the manifold, a shaft for supporting said valve, a plurality of tumblers carried by said shaft adapted to operatively connect said shaft with said valve, said tumblers having peripheral notches, a locking member normally in frictional engagement with said tumblers, means for rotating said tumblers for bringing said notches into alignment and into registry with said locking member, means for moving said locking member into said notches, and means for opening and closing said valve while said member engages said notches.

10. The combination with the carbureter and the intake manifold of an internal combustion engine said parts being connected by a common gas passage, of a butterfly valve disposed in said passage, a shaft for pivotally supporting said valve, a plurality of tumblers having peripheral notches carried by said shaft and disposed in an opening in said valve, one of said tumblers being rigid to said shaft and adapted to rotate the other tumblers for bringing the said notches into alignment, and a reciprocatable member carried by said valve adapted when moved away from said tumblers to lock said valve in the closed position and when moved towards said tumblers to engage said aligning notches for unlocking said valve.

11. The combination with a carbureter and an intake manifold said parts being connected by a common gas passage, of a butterfly valve controlling the flow of gas through said passage having a barrel, a shaft for supporting said valve, gears for operating said shaft, tumblers mounted on said shaft within said barrel, said tumblers hav-

ing peripheral notches, a locking member carried by said valve and movable towards and away from said tumblers, a graduated dial, a pointer for said dial, a rod connecting said gears with said pointer adapted to be rocked by the movement of said pointer for bringing said notches into alignment, and means for effecting the interlocking of said locking member with said notches for operatively connecting said shaft with said valve.

12. In a combination lock for motor vehicles, the combination with the carbureter and the intake manifold, said parts being connected by a common gas passage, of a butterfly valve disposed in said passage, means carried by said valve for locking the same in the closed position, tumblers having peripheral sockets disposed in the line of the rotatable axis of said valve, a shaft journalled in the line of said axis and supporting said valve and said tumblers, one of said tumblers being rigid to said shaft, means for rocking said shaft in opposite directions for bringing said sockets into registry with said locking means for effecting the release of said valve, a graduated dial, a pointer arranged to sweep said dial, said pointer operatively connected with said shaft adapted when moved in opposite directions into registry with certain graduations to effect the aligning of said sockets and the opening of said valve.

13. In a combination lock for motor vehicles, the combination with the carbureter and the intake manifold said parts being connected by a common gas passage, a valve disposed in said passage, tumblers carried by said valve having peripheral sockets, a shaft for pivotally supporting said valve and certain of said tumblers, one of said tumblers being rigid to said shaft, a reciprocatable locking member carried by said valve and movable towards and away from said tumblers adapted to be held in the locking position when the sockets of said tumblers are out of alignment, means for effecting the alignment of said sockets, means for moving said locking member into engagement with the aligning sockets for operatively connecting said valve with said shaft, and means for shifting said tumblers out of alignment for preventing the opening of the valve.

14. In a lock for automobiles, the combination with the carbureter and the intake manifold, said parts being connected by a common fuel passage, of a butterfly valve equipped with a combination mechanism comprising a shaft upon which said valve is journalled, a plurality of tumblers mounted on said shaft within the margins of the valve, one of said tumblers being rigid on said shaft and adapted to rotate the other tumblers when said shaft is rocked in op-

posite directions, said tumblers having similar sockets, a locking member movable on said valve towards and away from said tumblers adapted to be held by said tumblers in the locking position, said locking member adapted to be forced away from the locking position towards said tumblers when said sockets are brought into alignment, a dial

having numbered graduations, a pointer arranged to sweep said dial for selecting certain numbers comprising a combination by which said valve may be unlocked, and a train of gears for operatively connecting said pointer with said shaft. 10

In testimony whereof I affix my signature. 15

FREDERICK E. LARGE.
